UNITED STATES PATENT OFFICE

1,939,763

WATCH AND SIMILAR TIMEPIECE

Elof L. Carlson, Bristol, Conn., assignor to The
E. Ingraham Company, Bristol, Conn., a cor-
poration

Application July 27, 1932. Serial No. 624,952

14 Claims. (Cl. 58—90)

This invention relates to watches and similar timepieces, and particularly to means for effectively supporting the stems thereof; and it embodies improvements over the invention disclosed in my co-pending application for patent for Cases for timepieces filed January 30, 1932, Serial No. 589,786.

The invention has particular reference to watches of the wrist-strap type in which the movement is mounted in a case composed of two complementary flanged case members, the flanges of which are adapted for telescoping engagement and are provided with suitable complementary notches, so that when the case members are so engaged with the movement assembly between them, these notches will combine to form an opening which will permit the stem to extend exteriorly of the case.

In watches the cases of which are thus constructed, certain difficulties have been encountered in suitably supporting the stem relatively to the movement and in effectively excluding dust and other extraneous matter from the interior of the case.

It has been ascertained, from experience, that supporting means for the stem, in order to be really effective, must be rigidly mounted with relation to the watch-movement, so that the stem will be rigidly supported and located relatively to the movement rather than to the case and thus prevent lateral play and the binding or cramping of the stem which might result therefrom.

The main object of the invention is, therefore, to provide in a watch or other timepiece, particularly of the type referred to, means for supporting and guiding the stem, and particularly that portion of same which extends exteriorly of the case, in such a manner that, although the stem may be free for the rotation necessary in winding and setting the timepiece, any lateral movement will be substantially prevented and the stem will always be maintained in such position that its inner operative end will lie in proper relation to the parts operatively connected with it. The means whereby this support of the stem is accomplished is also provided with an arrangement whereby dust and other extraneous matter may be prevented from entering the case and thereby coming in contact with the parts of the movement.

The invention contemplates the combination, in a watch or the like, having a movement of ordinary type and a case, of means for rigidly supporting the winding and setting stem of the

movement in predetermined relation to the movement, these means comprising a bushing member rigidly mounted upon a fixed part of the movement supporting frame and provided not only with a bearing thereon but also with a bearing in the case itself; and the invention consists further in various details of this bushing member and the manner in which it is associated with other parts, as will be explained hereinafter more fully and finally claimed. 65

In the accompanying drawing illustrating the invention, in the several figures of which like parts are similarly designated,

Fig. 1 is a back view of a wrist watch of the conventional "baguette" type, to which the invention is applied. 70

Fig. 2 is an enlarged fragmentary sectional elevation taken on the line 2—2 of Fig. 1.

Fig. 3 is an enlarged fragmentary sectional elevation taken on the line 3—3 of Fig. 2; parts 75 being broken away in the interest of clearness.

Fig. 4 is an elevation of the winding stem and its bearing elements detached.

Fig. 5 is a section taken on the line 5—5 of Fig. 4. 80

Fig. 6 is a side elevation of the bushing member which provides bearing for the stem, and

Fig. 7 is an elevation of the stem.

The watch movement proper, parts of which only are illustrated in the drawing, comprises 85 the usual back movement plate 1 and front movement plate 2 connected and supported in suitable spaced relation by the customary pillars (not shown), and these plates have arranged between them and rigidly supported by them, 90 when they are appropriately connected, a bridge-plate 3 (see particularly Figs. 2, 4 and 5) having corner-lugs 4 and 5 which engage suitable locating and supporting bearing openings in the back and front mounting-plates 1 and 2 95 respectively.

The winding and setting pinion 6 is, in accordance with the present invention, somewhat modified from its usual form and includes a cylindrical hub 7 extending through a complementary opening 8 in the bridge-plate 3 so as to have a rotative bearing therein. As will be seen by reference particularly to Fig. 2, this hub is of such a length as to extend for some distance past the face of the bridge-plate opposite to that against 100 which the pinion 6 proper lies, and upon this extending portion of the hub 7 is assembled, with a force, friction fit, a bushing member 9 interiorly recessed at 10 to receive the hub extension, and provided with an offstanding base 110

flange 11 in engagement with the bridge-plate and forming a relatively extensive lateral bearing for the bushing member. By this arrangement of parts, it will be seen that the pinion 6 and the flange 11 of the bushing member 9 both bear against the bridge-plate 3 in such a manner as to be rotatable relatively thereto but relatively rigid on their axis of rotation.

The bushing 9 has an axial bore 12 which 10 communicates with a bore 13 in the hub 7 of the pinion 6, these two bores providing a bearing for the stem 14 which has a square or other non-cylindrical end 15 to provide a turning connection between the stem and the pinion 6, the interior of the bore 13 of the hub 7 of which is broached as indicated at 16, Fig. 5, for engagement therewith. The exteriorly extending end of the stem is threaded at 17 and is provided with a turn-button 18 by which it may be 20 rotated, as is customary.

The case which, as hereinbefore indicated, is of more or less conventional type, is formed of a back member 19 having a flange 20, and a front member 21 having a flange 22 and provided with the usual face opening 23 and bezel 24 against which bears the crystal 25 held in place by a retaining member 26 in a conventional manner. The flanges 20 and 22 of the back and front case members 19 and 21 are provided with suitable complementary notches 27 and 28, respectively, which will permit the assembly of the case members upon the movement assembly by passing around the outwardly extending portion of the stem and, when the two case members are fully assembled, as illustrated in Fig. 3, will form an opening through which the stem extends.

As will be apparent, particularly from an inspection of Figs. 2, 3, 4 and 6, the bushing member 9 is provided, adjacent to its outwardly extending end portion, with a circumferential recess 29 with which the notches of the case members engage, the recess 29 providing a shoulder 30 which overlies and forms an effective dust seal for the opening formed by the notches of the case members, and a shoulder 31 underlying the opening and complementary to the overlying shoulder 30.

It will be apparent from the foregoing description that when the case members are assembled upon the movement, with their notches in engagement with the recess 29 of the bushing member 9, the arcuate surfaces of the notches which form the opening through which the bushing member passes will form a bearing in the case for the bushing member 9 and hence for the stem 14, which has its bearing in the bushing member.

Thus the bushing member 9 has two axially spaced bearings in which it may rotate with the stem 14, one of these bearings being carried by a fixed member of the movement frame and being so rigid as to substantially prevent any such lateral displacement of the stem, which might be imparted thereto by relative movement of the case members and the movement frame, as would cause the stem to bind or cramp and thus have its action impaired.

It will be seen, from an inspection of Fig. 2, 70 that, in addition to its other functions, the bushing member 9, by virtue of the depth of its recess 10 and the arrangement of its shoulder 30, serves to limit the inward and outward movement of the stem 14 whereby it is adjusted from 75 a winding to a setting position and vice versa.

Various changes and modifications are considered to be within the spirit of the invention and the scope of the following claims.

I claim:

1. In a watch or the like, a movement including a frame, a case for said movement, a stem extending exteriorly of said case, and means for supporting said stem against movement transversely of the axis of said stem and including a bushing member having a bearing in said frame and a bearing in said case. 80 85

2. In a watch or the like, a movement including a frame, a case for said movement, said movement provided with a stem extending exteriorly of said case, and a bushing member providing a support for said stem against movement transversely of the axis of said stem, said bushing member being rigidly and rotatably supported by said frame and having a bearing in said case. 90 95

3. In a watch or the like, a movement including a frame, a case for said movement, said movement provided with a stem extending exteriorly of said case, and a bushing member for said stem embracing same throughout a portion 100 of its length, said bushing member provided with axially spaced bearings supported by said frame and case respectively, whereby said stem is rigidly supported against movement transversely of the axis of said stem. 100 105

4. In a watch or the like, a movement having a frame including a bridge plate, a case for said movement, said movement provided with a stem extending exteriorly of said case, and a bushing member for supporting said stem against movement transversely of the axis of said stem, said bushing member supported by said bridge plate and having a bearing in said case. 110

5. In a watch or the like, a movement having a frame, a case for said movement, said movement provided with a stem extending exteriorly of said case, and a bushing member for supporting said stem against movement transversely of the axis of said stem, said bushing member having an axially rigid rotative bearing relatively 115 120 to said frame and a rotative bearing in said case.

6. In a watch or the like, a movement having a frame including a bridge plate, a case for said movement, said movement provided with a stem extending exteriorly of said case, and a bushing member for supporting said stem against movement transversely of the axis of said stem, said bushing member having an axially rigid rotative bearing on said bridge plate and a rotative bearing in said case. 125 130

7. In a watch or the like, a movement having a frame, a case for said movement, winding and setting mechanism for said movement including a stem extending exteriorly of said case and a gear, a bushing providing a bearing for said stem, and a member carried by said frame and providing a support for said bushing, said bushing and gear provided with complementary means whereby they may be axially rigidly but rotatably connected with and supported by said member. 135 140

8. In a watch or the like, a movement having a frame, a case for said movement, winding and setting mechanism for said movement including a stem extending exteriorly of said case and a gear, a bushing providing a bearing for said stem, and a member carried by said frame and providing a support for said bushing, said bushing and gear provided with complementary means whereby they may be axially rigidly but rota- 145 150
